UNITED STATES PATENT OFFICE.

WINGATE S. THOMAS, OF CHICAGO, ILLINOIS, ASSIGNOR TO KNAPP BROTHERS MANUFACTURING COMPANY, OF CHICAGO, ILLINOIS, A CORPORATION OF ILLINOIS.

BUILDING CONSTRUCTION AND THE LIKE.

Application filed November 26, 1923. Serial No. 677,130.

This invention has to do with certain improvements in building constructions and the like. The invention has reference particularly to improvements in the construction of window casings, door casings, and similar structures. The invention has reference particularly to improvements in the form and construction of such locations as the window sills, tops of window and door casings, etc.

More particularly the invention has to do with improvements in constructions of the above class which are made of metal. The invention has reference to the construction of window sills and the top portions of window casings, and has for its main object to provide a unitary structure which will extend clear across the width of the window or door from one side to the other, and provide the two adjacent corners for direct connection with the sides of the window or door casing. That is to say, it is an object of the invention to provide a unitary casing structure including the full width of the casing and the two adjacent corners.

Inasmuch as the features of the invention are particularly well adapted for window sills and the like, I have illustrated and will particularly describe these features as embodied in a window sill construction. In so doing, however, I wish to make it clear that I do not intend thereby to limit the features of the invention to this particular or any other particular class of use, since it will be evident that the features of the invention may be used advantageously for other purposes.

In the drawing:

Figure 1 shows a face view of a window sill embodying the features of the present invention, the central portion thereof being broken away so as to shorten up the figure, and a portion of one of the side casing members being shown in place in connection with one end of the window sill; and

Fig. 2 shows a cross section taken on the line 2—2 of Fig. 1, looking in the direction of the arrows, and also shows the adjacent window structure in place.

The window sill itself comprises a strip of sheet metal suitably formed to establish the flattened sill portion 5 whose forward edge is curved downwardly on an easy curve 6 to a point 7 where it becomes practically tangent to the surface 8 of the plastering 9

which finishes the interior of the wall 10. This portion constitutes a facing flange. The lower end of the window sill is folded backwardly on a sharp angle as shown at 11, and its extreme edge 12 is turned down into a vertical position, so that it will lie flush against the permanent structure of the wall. In some cases a nailing strip 13 is provided on the front face of the permanent wall structure; and when this type of construction exists the flange 12 should set squarely against this nailing strip to which it may be suitably secured.

The rear edge 14 of the window sill itself is preferably secured to a nailing strip 15 on the top of the permanent wall structure; and if desired, a filling or grouting of cement or the like 16 may be provided to fill in the space between the window sill and the permanent structure.

Ordinarily, the window sill will be provided with a series of perforations 17 adjacent to the upper edge of the flange 12, so that the plaster 9 may be forced through these perforations and thus secure the lower edge of the window sill very firmly with respect to the plaster itself.

The ends 18 and 19 of the window sill are curved around at right angles as clearly shown in Fig. 1, and the extreme end portions of the metal strip are inset as shown at 20 and 21 to establish fitting flanges which are shouldered back from the main body of the window sill to establish the shoulders 22 and 23. These shoulders are of the same depth as the thickness of the metal 24 which is used for the side portions of the casing structure, so that when the sides of the casing are set into place with respect to the window sill a perfectly flush and finished condition may be provided at the junction as shown in Fig. 2 at the point 25.

The above construction also establishes a very firm connection between the window sill itself and the lower portions of the sides of the window casing.

I wish to emphasize the fact that while I have herein illustrated and described the invention as embodied within a window sill, still the invention may also be used to advantage in the construction of the other portions of the window casing, in the construction of the top portions of door casings, and in any other similar locations.

Therefore, while I have herein shown and

described only a single embodiment of the features of my present invention, still I do not limit myself to the same except as I may do so in the claims.

5 I claim:

1. As a new article of manufacture, a casing strip for the casing of a door or window comprising an integrally formed strip of metal having a longitudinally extending bend to afford a sill flange and a facing flange at approximately right angles to one another, said strip having one of its ends extended in right angled relation to the intermediate portion of said strip and similarly provided with a longitudinally extending bend affording sill and facing extensions merging unbrokenly into the sill and facing flanges of the intermediate portion of the strip, and the terminal portions of said extension being inwardly offset to afford a shoulder at a point behind the extreme end thereof, in combination with a side strip longitudinally bent to conform to the configuration of the end extension and abut against the shoulder thereof to bring the outer face of said side strip into flush relation with the face of said extension and to

bring the offset end portion of said extension into underlapped relation to the end of said side strip, substantially as described.

2. As a new article of manufacture, a casing strip for the casing of a door or window comprising an integrally formed strip of metal having a longitudinally extending bend to afford a sill flange and a facing flange at approximately right angles to one another, said strip having one of its ends extended in right angles to said strip and similarly provided with a longitudinally extending bend affording sill and facing extensions merging unbrokenly into the sill and facing flanges of the strip, and the terminal portions of said extension being inwardly offset to afford a shoulder at a point behind the extreme end thereof, in combination with a side strip longitudinally bent to conform to the configuration of the end extension and abut against the shoulder thereof to bring the outer face of said side strip into flush relation with the face of said extension and to bring the offset end portion of said extension into underlapped relation to the end of said side strip, substantially as described.
